DESIGN FOR A SUNGLASS FRAME

Joseph R. Watkins, Dover, N. J., assignor to Foster Grant Co., Inc., Leominster, Mass., a corporation of Massachusetts

Application December 14, 1948, Serial No. 150,155

Term of patent 14 years

(Cl. D57—1)

To all whom it may concern:

Be it known that I, Joseph R. Watkins, a citizen of the United States, residing at Dover, Morris County, State of New Jersey, have invented a new, original, and ornamental Design for a Sunglass Frame, of which the following is a specification, reference being had to the accompanying drawings, forming part thereof, in which:

Fig. 1 is a front view of a sunglass frame, showing my new design; and

Fig. 2 is a top plan view thereof.

The essential features of the design are shown in full lines.

I claim:

The ornamental design for a sunglass frame, substantially as shown and described.

JOSEPH R. WATKINS.
